CLAIM

I claim the ornamental design for a pacifier, as shown and described.

DESCRIPTION

FIG. 1 is a top, left, front perspective view of a pacifier showing my new design;

FIG. 2 is a top plan view of the pacifier of FIG. 1;

FIG. 3 is a bottom plan view of the pacifier of FIG. 1;

FIG. 4 is a right side elevational view of the pacifier of FIG. 1, the left side elevational view being a mirror image of FIG. 4;

FIG. 5 is a rear elevational view of the pacifier of FIG. 1; and,

FIG. 6 is a front elevational view of the pacifier of FIG. 1.
